Patented Sept. 26, 1916.

UNITED STATES PATENT OFFICE.

FRANK K. FREEMAN, OF KENNAN, WISCONSIN.

TOOL FOR HANDLING DYNAMITE.

1,199,259.

Specification of Letters Patent. Patented Sept. 26, 1916.

Application filed May 1, 1916. Serial No. 94,714.

To all whom it may concern:

Be it known that I, FRANK K. FREEMAN, a citizen of the United States, residing at Kennan, in the county of Price, State of Wisconsin, have invented certain new and useful Improvements in Tools for Handling Dynamite; and I do hereby declare the following to be a full, clear, and exact description of the invention, such as will enable others skilled in the art to which it appertains to make and use the same.

This invention relates to tools for handling dynamite.

The object of the invention is to provide a tool of the type named embodying an improved construction whereby the various operations incident to handling dynamite can be performed with facility.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a plan view of a tool constructed in accordance with the invention, the jaws of said tool being shown closed; Fig. 2, a fragment of what is shown in Fig. 1 with the jaws in open position; Fig. 3, a section on the line 3—3 of Fig. 1; Fig. 4, a perspective view of one of the elements of the tool, and Fig. 5, a perspective view of the other element.

Referring to the drawings the improved tool is shown as comprising pivotally connected members A and B corresponding ends of which are shaped to form handles 10 and 11 respectively, while the other corresponding ends constitute the coöperating jaws 12 and 13 respectively. The jaws 12 and 13 are hollowed out to form coöperating knife edges 14 and 15 respectively for the purpose of providing the necessary cutters to sever

fuses in handling dynamite. The outer end of the edges 14 and 15 are roughened or serrated as at 16 to provide means for crimping a cap on a fuse.

The jaw 13 carries on its outer end a punch 17 to provide the necessary cavity in a stick of dynamite for inserting the explosion cap. Formed on the outer edge of the jaw 13 is a ring 18 of a diameter suitable to receive a stick of dynamite. The jaw 13 is provided with a passage 19 one end of which communicates with the interior of the ring 18. Slidably mounted in this passage is a chisel element 20 provided with a longitudinal slot 21 through which is engaged a pin 22 carried by the jaw 13 and whereby the element 20 is secured against detachment from the jaw 13. Formed on the member A is an arm 23 which coöperates with the inner end of the chisel element 20 as the jaws 12 and 13 are closed for the purpose of forcing the chisel element to the position shown in Fig. 1. By this construction it will be apparent that when the jaws 12 and 13 are in the position shown in Fig. 2 and a stick of dynamite is inserted in the ring 18 and the jaws 12 and 13 then closed the arm 23 will coöperate with the chisel element 20 and force the latter into the stick of dynamite to split the same.

What is claimed is:

A tool of the class described comprising pivotally connected members corresponding ends of which form handles and the other corresponding end coöperating jaws, a ring on the outer edge of one of said jaws, a chisel slidably mounted in said jaw and adapted to enter the ring when moved in one direction, and an arm on one of the members coöperating with said chisel when the jaws are moved to closed position to force said chisel into the ring.

In testimony whereof, I affix my signature, in the presence of two witnesses.

FRANK K. FREEMAN.

Witnesses:

CLARENCE L. PECK,
JAMES FREEMAN.
